UNITED STATES PATENT OFFICE.

JOSEPH W. SCHLOSS, OF NEW YORK, N. Y.

DESIGN FOR TRIMMING.

SPECIFICATION forming part of Design No. 21,831, dated September 6, 1892.

Application filed July 29, 1892. Serial No. 441,622. Term of patent 3½ years.

To all whom it may concern:

Be it known that I, JOSEPH W. SCHLOSS, a citizen of the United States, residing at New York, in the county of New York and State 5 of New York, have invented a certain new and original Design for Fur Trimming, of which the following is a full, clear, and exact description.

My new and original design is for fur trimming.

The figure is a side elevation of fur trimming embodying the design.

The features of the design are, first, of a fur band-like figure A, having its hair a standing substantially at right angles to the length 15 of the band; second, a braided band-like figure B, arranged along one side or edge of the fur band, and, third, a braided cord-like figure C, arranged upon the face of the fur band 20 and along one side, portions of which project across and beyond the band B, the parts which

so project being formed into groups b of loops. Between the groups and upon the face of the fur band the cord is formed into single loops b', thus giving a unique and ornamental appearance to the trimming, as illustrated in the drawing.

I am aware of a design for fur trimming in which the first and second features above mentioned of my design are shown; but the leading feature of my design is the cord-like figure C, arranged as described and in connection with the other features.

I claim—

The design for fur trimming herein shown 35 and described.

In testimony whereof I subscribe my signature in presence of two witnesses.

JOSEPH W. SCHLOSS.
